PHONOGRAPH CARTRIDGE

Robert Louis Deschamps, West Chicago, and Marvin B. Lorig, Skokie, Ill., assignors, by mesne assignments, to said Lorig

Filed June 26, 1964, Ser. No. 80,605

Term of patent 14 years

(Cl. D26—14)

FIG. 1.

FIG. 2.

FIG. 3.

FIG. 4.

FIG. 5.

FIG. 6.

FIGURE 1 is a perspective view of a phonograph cartridge illustrating the new design;

FIGURE 2 is a side elevational view, the opposite side being substantially a mirror image thereof;

FIGURE 3 is a front end elevational view;

FIGURE 4 is a top plan view;

FIGURE 5 is a bottom view; and

FIGURE 6 is a rear end elevational view thereof.

We claim:

The ornamental design for a phonograph cartridge, substantially as shown and described.
